MECHANICAL PENCIL AND METHOD OF
MAKING IT

Samuel E. Linton, Jr., Shelbyville, Tenn.

Application August 6, 1936, Serial No. 94,678

5 Claims. (Cl. 120—18)

This invention relates to pencils of that type in which the lead is propelled at intervals beyond the pointed end element of the pencil by rotating the barrel with relation to said pointed end or to the cap, such pencils having therein a spiral element and a central tube for containing the lead, the tube being provided with a follower engaging the spiral element so that as the barrel is turned with relation to the extremity of the pencil, the follower engaging the screw will force the lead out. Particularly, this invention relates to a method of making pencils of this type.

The main object of my invention is to simplify the manufacture of these pencils so as to greatly reduce the cost thereof without in any way reducing the quality of the pencil and particularly to form the barrel of two grooved sections of wood or composition, placing the pencil propelling mechanism within the groove of one section and pressing the other section of the barrel down upon the propelling mechanism so that the spiral which constitutes the screw of the propelling mechanism shall be forced into and slightly embedded in the material of the barrel and into the glue 25 coating the faces of the two sections.

Other objects will appear in the course of the following description.

My invention is illustrated in the accompanying drawing wherein:

30 Figure 1 is a side elevation of the complete pencil;

Figure 2 is an enlarged vertical section on the line 2—2 of Figure 1;

Figure 3 is a section on the line 3—3 of Figure 2;

35 Figure 4 is a face view of a slab or slat of wood or composition formed with a plurality of grooves for the reception of the propelling mechanism of the pencil;

Figure 5 is a like view to Figure 4, but showing 40 the spiral, central tube and the conical metal extremity of the pencil with the spiral forced into the groove in the wood and embedded therein;

Figure 6 is a cross-sectional view through two 45 slabs pressed against each other and holding a plurality of propelling mechanisms within the grooves of the slabs;

Figure 7 is an enlarged view showing in an 50 exaggerated manner the way in which the spiral of the propelling mechanism is embedded in the wood or composition.

Referring to the drawing, particularly to Figure 2, it will be seen that the complete pencil comprises a barrel 10 of wood, composition or like 55 material, this barrel being tubular. Extending

longitudinally through the barrel is a small metallic tube 11 which at one end terminates in a pointed conical metallic head 12 formed with the annular recesses 13. This head 12 is provided with a central bore through which the lead 14 extends. Disposed within the bore of the tube 11 is a follower 15. The tube 11 is formed with a longitudinally extending slot 16 and the follower is provided with two outwardly projecting lugs 17 which extend through this slot. Surrounding the 10 tubular member 11 and disposed within the bore of the barrel 10 is a spiral 18 of wire which constitutes a screw. The lugs 17 extend into this wire spiral so that if the barrel 10 be held and the head 12 be rotated, the follower will travel up or 15 down the spiral, depending upon the direction of rotation. Disposed upon the end of the barrel opposite the head 12 is a cap 19 having a central bore, and within this cap is a washer 20. The tube 11 extends through the central opening of 20 the cap and is flanged over upon the washer, as at 21. This cap is provided with a small lug 22 which engages in the slot 16 of the tube 11, so that when the cap is rotated, it will cause a rotation of the tube 11. A rubber eraser 23 is carried by the cap 25 in the usual manner. So far, I have described mechanism which is well known.

My invention does not relate to the details of construction of the propelling mechanism of the pencil itself but to the method of completing such 30 pencil by engaging the propelling mechanism with the barrel. In completing pencils of this type, a board, slat or slab of wood, or composition, designated A in Figure 4, is formed with a plurality of longitudinal parallel grooves a. The slab or board 35 has a length equal to the distance between the inner end of the head 12 and the final turn of the spiral 11, as shown in Figure 5. The central tube 14 with the spiral 11 is placed in one of the grooves a of one slot with the head 12 abutting against 40 one end of the slat. There are a plurality of grooves in the slab A and each one of these grooves is fitted with the propelling mechanism of one pencil until all of the grooves are filled. The surface of a slab A' is then coated with glue 45 and pressed against the slab A in the manner shown in Figure 6, and the two slabs are forced together so tightly that the spiral 11 is forced into the relatively soft wood or composition, so as to be slightly embedded therein, as shown in an ex- 50 aggerated manner in Figure 7. When the glue is set so that the two slabs with the pencil propelling mechanisms therein are joined firmly, the conjoined slabs are cut, as shown by dotted lines in Figure 6 at a' and the pencil is run through a 55

molding machine and the barrels cut out in any desired shape or size in cross-section either round, hexagonal or any other shape transversely. It is to be understood that the conjoined slats in the 5 form shown in Figure 6 may be run through a molding machine and the barrels cut out in any shape or size without necessarily first dividing the slab into pencil sections, as shown by the dotted lines in Figure 6. After the barrels have been 10 shaped into the desired form, they are then painted any color desired and ready for the attachment of the remainder of the pencil mechanism, namely, the attachment of the cap.

It is to be understood that when the faces of 15 the two sections A and A' are covered with glue, a slight layer of glue is also applied in the grooves a and that thus when the two sections A and A' are pressed together, the outer faces of the spiral 18 will be also embedded in this glue and rigidly 20 connected to the sections of the wood or composition by the glue.

The above described process of manufacturing 25 pencils will lower the cost of this pencil very greatly so that, as a matter of fact, these pencils 25 may be retailed at five cents whereas the cheapest similar mechanical pencil on the market retails for ten cents. This is because the barrel of 30 a mechanical pencil is the most expensive single item of such pencils. These mechanical pencils 30 are usually made by forming a bore through the body of composition and inserting the mechanism in the bore. In all of the spiral feeding mechanisms known to me, and I have examined all of 35 the leading makes of mechanical pencils, the spiral is loose within the pencil barrel and the feeding mechanism is held in place by the point being attached to the barrel, the ferrule extending down into the actual barrel and being attached to the spiral mechanism to properly propel 40 the lead back and forth.

While I have shown a spiral which is made of material that is circular in cross section, I wish it distinctly understood that this spiral might be made of material which is square or which is 45 flat and broad.

What is claimed is:—

1. The method of making pencils which consists in longitudinally grooving a slab of material, pressing a lead propelling mechanism into the 50 groove, covering the face of a second grooved slab with glue, placing this slab with the grooves downward upon the first named slab, and pressing the

two slabs against each other under a pressure which shall embed the propelling mechanism within the grooves.

2. The method of making pencils which consists in forming a slab of wood or composition 5 with a plurality of longitudinally extending parallel grooves, pressing a plurality of lead propelling mechanisms each into one of said grooves, covering the face of another slab with glue and placing the second slab in adhering engagement 10 with the first named slab and forcing the two slabs against each other with a pressure which shall embed the propelling mechanism into the walls of the grooves, then dividing the conjoined slabs to form pencil barrels and shaping the pen- 15 cil barrels.

3. The method of making pencils which consists in forming a plurality of parallel grooves in a slab of material, disposing a lead propelling mechanism within said grooves, the propelling 20 mechanism including a metallic spiral, the head of each propelling mechanism being disposed to abut against the end of the slab, covering the grooved face of a second slab with glue, pressing it against the face of the first named slab 25 with such force as to slightly embed the spiral in the material of the two conjoined slabs, then cutting and forming a plurality of pencil barrels from said conjoined slabs.

4. The method of making pencils which consists 30 in forming a plurality of parallel grooves in a slab of relatively soft material, disposing a lead propelling mechanism within said grooves, the mechanism including a metallic spiral, covering the grooved face of a second slab with glue and 35 pressing it against the face of the first named slab with such force as to slightly embed the spiral in the material of the two conjoined slabs and in the glue and then cutting and forming a plurality of pencil barrels from said conjoined slabs. 40

5. The method of making pencils which consists 45 in forming a plurality of grooves in a slab of material, disposing lead propelling mechanisms within said grooves, which mechanism includes a metallic spiral covering the grooved face of a second slab with glue and pressing it against the face of the first named slab to thereby embed the spiral in the layer of glue and then cutting and forming a plurality of pencil barrels from said 50 conjoined slabs, the glue when hardened holding the spiral from longitudinal movement.
